UNITED STATES PATENT OFFICE.

HANS A. PENNINGTON, OF CHICAGO, ILLINOIS.

DESIGN FOR A PINCUSHION.

Application filed April 11, 1923. Serial No. 5,778. Term of patent 3½ years.

To all whom it may concern:

Be it known that I, HANS A. PENNINGTON, a citizen of the United States, residing at Chicago, in the county of Cook and State of Illinois, have invented a new, original, and ornamental Design for Pincushions, of which the following is a specification, reference being had to the accompanying drawings, forming a part thereof.

The figure is an elevation of the pincushion, showing the new design.

I claim:

The ornamental design for a pincushion as shown.

In testimony whereof I have hereunto affixed my signature.

HANS A. PENNINGTON.
